UNITED STATES PATENT OFFICE

2,073,597

INDUCTION ELECTRIC FURNACE

Edwin Fitch Northrup, Princeton, N. J., assignor
to Ajax Electrothermic Corporation, Ajax Park,
N. J., a corporation of New Jersey

Application May 22, 1930, Serial No. 454,581
Renewed September 3, 1936

17 Claims. (Cl. 13—26)

My invention relates to improvements in the structure of electric induction furnaces.

A purpose of my invention is to shield the magnetic parts of an induction electric furnace from excessive heating due to stray flux from the inductor coil.

A further purpose is to permit the use of magnetic steel structure in an induction electric furnace in place of more expensive non-magnetic alloys.

A further purpose is to conduct the heat from the stray field developed in the structure of an induction electric furnace to a distant point where the heat is dissipated.

A further purpose is to make it unnecessary to use compensator coils or magnetic return circuits about the inductor of a furnace and yet to not limit the power input to the furnace.

A further purpose is to increase the metallic structural support of an inductor coil without increasing the coil losses.

A further purpose is to consume the energy of the stray field about an inductor coil in inducing current in a non-magnetic shield, thus preventing the lines of force from proceeding further.

Further purposes appear in the specification and in the claims.

In the drawings I illustrate two only of the desirable forms of my invention, choosing them from the standpoint of their efficiency in carrying out my purpose and of the ease with which they may be illustrated.

Figure 1 is a top plan view of an induction furnace to which my invention has been applied. The cover of the furnace has been removed for more convenient illustration of the inductor structure, and certain non-essential details have been omitted.

Figure 2 is a side elevation of the furnace of Figure 1.

Figure 3 is a fragmentary section taken on the line 3—3 of Figure 2, omitting structure in the background.

Figure 4 is a temperature-time curve of a test showing an example of the use which my invention serves.

Figure 5 corresponds generally to Figure 3, but shows a variant application of my invention.

In the drawings similar numerals refer to like parts throughout.

A great deal of difficulty has been met with in the manufacture and use of induction electric furnaces of the coreless type because of the interference of the magnetic return circuit of the furnace with the use of normal steel or iron for

the frame parts of the furnace. This difficulty has been greatest with the larger furnaces because, with the increased weight, the necessity for strong frame members and the size of these members are increased.

Attempts have been made to avoid the difficulty in various ways, as by additional spacing of the frame parts from the furnace, the provision of a magnetic return circuit for the furnace, which is independent of the frame of the furnace by the use of an additional inductor coil (compensator coil) outside of the main inductor coil to take care of stray field, and by various other means. All of these offer difficulties in some constructions.

Compensator coils are disclosed in prior patents, for example my Patent No. 1,744,983, granted January 28, 1930, for Inductor furnace, the patent to Jones, No. 1,608,560, granted November 30, 1926, for Coil system, and that to Banning, No. 1,667,715, granted May 1, 1928, for Inductive unit and the like.

Furnace designers have therefore favored the use of non-magnetic alloys for the structural parts, particularly in the case of the larger induction furnaces. Alloys of the brass type are lacking in the requisite tensile strength. Ferrous non-magnetic alloys, as for example ascoloy (an iron alloy containing 8% of nickel and 18% of chromium, generally classed as a stainless steel), are quite expensive, and I therefore aim to eliminate such materials or to reduce them to a minimum.

My invention aims to absorb stray lines of force from the furnace with a minimum of interference with the construction of the furnace frame and with a maximum cooling effect to dissipate the heat due to the absorption.

By my invention I place a non-magnetic shield between the inductor coil and the magnetic parts of the furnace. By the introduction of such a non-magnetic shield I cut off the stray field of the inductor coil from the magnetic parts. In this way I avoid the hysteresis heating which would otherwise take place in the magnetic parts, and which by my invention easily may be greatly reduced or may be eliminated.

I preferably use a material for my shield which has a much lower electrical resistance than such common magnetic materials as steel. As an example of one good shield material I suggest copper.

Steel and similar magnetic materials have relatively low heat conductivities as compared with non-magnetic materials such as copper. There-

fore, by using a shield having a high heat conductivity, the heat due to RI^2 energy losses and to conduction from the crucible and charge will be rapidly distributed to points remote from the furnace pool, instead of remaining concentrated in the portions adjacent to the inductor coil, as would be the case in a material of low heat conductivity.

Since the flux will travel in wide curves extending outward from the ends of the inductor coil, my shield should preferably be longer than the coil to cut off all stray field from the magnetic parts.

As seen in Figures 1 and 2, the inductor coil 10 surrounds the crucible 11 containing the charge. The inductor coil is supported by struts 12 from the outer casing of the furnace. Current is supplied to the inductor coil at the points 13 and 13' through leads 14, 14' from a generator, not shown. The power factor may be desirably corrected by the condenser 142.

In the outer casing of the furnace heat insulation 15 completely surrounds the inductor coil. One material which has been found satisfactory because of its heat insulating properties and strength is asbestos board.

The sides of the furnace nearest the magnetic supports are covered with non-magnetic shields 16, preferably of copper. For structural reasons these should extend the full distance to the edges so that they may be held by the angle strip 17 and 18, preferably of brass or similar non-magnetic material.

Beyond the shield and the angle plates diagonal supporting strips 19 of magnetic material extend from the top of the furnace at the front to the bottom at the rear. At the upper end of the supporting strips trunnion plates 20 supporting trunnions 21 are secured by bolts 22 extending through the diagonal supporting strips and in some cases through the shield and heat insulating material.

At the base of the diagonal supporting strips, bolts 23 secure them to flanges 24 on an angle strip 25 extending along the bottom back edge of the furnace. A clevis 26 is also placed at the bottom on each side for engagement by hooks on a crane used to tilt the furnace about one of the sets of trunnions. At the front of the furnace a corner strip 27 unites the ends of the angle strips 17.

As best seen in Figure 3, the non-magnetic shield 16 covers the entire face of the furnace inside of the magnetic diagonal supporting member 19 and trunnion plate 20.

The distance between the frame parts of the furnace and the inductor coil is selected so as to give ample room for an intermediate return magnetic circuit and so that the lines of force tending to heat the metal of the frame will be a relatively small and stray part of the magnetic field. Notwithstanding this, the low reluctance of the magnetic path through magnetic frame parts so reduces the reluctance of the return circuit that an excessive part of the magnetic return crowds through these frame parts, excessively heating the frame in the absence of some means of protection.

The magnetic lines which tend to pass beyond the shield 16 are forced to pass into, if not through, this shield. In their travel within the shield they set up electric currents in the metal of the shield, frittering away their magnetomotive force in the passage.

75 The depth to which the lines of force extend

into the nonmagnetic electrically conducting shield restricts the depth at which the electric currents are induced within the shield and the extent of current induction there varies with the strength of the magnetic force which progressively decreases within the shield.

A thickness of shield may be selected for any given frequency which will wholly or effectively, for all practical purposes, absorb the lines of force, so that no lines of force, or not enough to produce undesirable effects, pass through the shield. Here, as in the case of the induction of current within any secondary, complete absorption of the magnetomotive force of the stray field within the shield represents a thickness of shield corresponding approximately to three times the "effective depth of penetration", often called simply the "depth of penetration", of the current within the shield.

For example, for a frequency of one thousand cycles, the thickness of the shield 16 should be about one-quarter inch, preferably of copper. For a discussion of "effective depth of penetration" see my Patents No. 1,694,781, granted December 11, 1928, for Induction electric furnace, and No. 1,694,792, granted December 11, 1928, for High frequency induction furnace, and Steinmetz, "Theory and Calculation of Transient Electric Phenomena and Oscillations", Chapters VI and VII, and especially page 383.

Material on the inside of the shield 16 should desirably be non-magnetic. Thus in Figure 3, the washers 28 may be of magnetic material, but the bolt 22, the nut 29 and the washer 30 inside the shield 16 should preferably be of ascoloy.

However, as the direction of flux near the bolt is vertical, and the vertical projected area of the bolt which will intercept flux is very small, I may form my bolt of magnetic material without very high heating in it, although high heating would occur in large structural members if they were similarly exposed. Besides performing the function of a shield, the non-magnetic plate 16 adds additional strength to the structure, particularly where, as shown in my drawings, it extends under the angle strips to be engaged by them and united to them if desired.

Any predetermined approach to complete absorption of the stray field magnetomotive force within the shield may be effected which proves desirable under the conditions of intended use.

Tests of this invention show that a copper shield substantially absorbing all of the stray field does not heat anywhere nearly as much as the magnetic frame parts of the furnace heat in the absence of the shield, in such an arrangement as is shown in Figures 1, 2 and 3, for example. This is the case notwithstanding that the shield is closer to the coil and therefore is located in a stronger part of the return circuit magnetic field than the magnetic frame parts of the furnace. The difference in heating seems out of proportion to such as would be anticipated from the better distribution of heat within the shield on account of the higher thermal conductivity of the copper and the consequent better heat distribution and heat dissipation from the larger copper surface.

Figure 4 illustrates the result of a test made upon a furnace in which the magnetic structural members on one side were shielded by copper as here shown, and those on the other side of the furnace were not provided with shielding. The distance from the center of the coil to the mag-

netizable frame parts was the same on both sides of the furnace, so that the results are comparable. In the curve, the ordinates indicate temperature in degrees centigrade, while the abscissae are time in minutes.

During the test the room temperature rose, as shown by the curve A. The shield 16 on one side of the furnace increased in temperature as shown by the curve B, while the protected structural diagonal 19 increased in temperature along the curve C.

On the other side of the furnace, the unprotected structural diagonal increased in temperature as indicated by the curve D. Thus after 15 one hundred sixty minutes the room temperature was 21° C., the temperature of the shield and of the protected diagonal was approximately 26° C., while the temperature of the unprotected diagonal member rose to 92°. All curves are extrapolated beyond one hundred sixty minutes.

It will of course be understood that the test here recorded is merely illustrative and is not intended to limit the invention to any conditions of use.

25 This very considerable reduction in temperature is more remarkable because the copper is located closer to the inductor coil, and therefore within a stronger field than the magnetizable material. In so far as additional flux might 30 pass through the magnetizable frame parts, because they offer a path of lower reluctance for the return of the field, no change has been made in the position of these magnetizable parts.

In Figure 5, I show by way of illustration a less 35 desirable form of my invention. In this form I omit the non-magnetic shield 16 and instead place a non-magnetic covering 16' on the exposed surfaces of the magnetic supports 19 and 20. For example, the diagonal support 19 may 40 be formed from a copper and a steel billet which are placed together while highly heated and rolled, to weld the copper to the surface of the steel.

The form of Figure 5 lacks the advantage of 45 increased structural strength found in my other form, and is illustrated by me merely to show that it is not necessary that the non-magnetic shield be a separate member from the magnetic structural pieces. In this form the washers 28' 50 will preferably be of ascoloy since they are inside the shield.

The construction of Figures 1, 2 and 3 is considerably better than that of Figure 5 from the standpoint both of more nearly total absorption 55 of the lines of force and from the collateral standpoint that the larger area and more extended physical distribution of the copper in Figures 1-3, offers not only a larger area within which the stray field may be intercepted and 60 dissipated but also a much larger area for convection, conduction and radiation of heat from the shield.

However, tests of the construction of Figures 1, 2 and 3 have shown a reduction of temperature 65 in the copper when used below that of the magnetic frame parts when the copper is not used, out of seeming proportion to the reduction of temperature which the explanation above would lead one to expect.

70 In view of my invention and disclosure variations and modifications to meet individual whim or particular need will doubtless become evident to others skilled in the art, to obtain part or all of the benefits of my invention without copying 75 the structure shown, and I, therefore, claim all

such in so far as they fall within the reasonable spirit and scope of my invention.

Having thus described my invention, what I claim as new and desire to secure by Letters Patent is:

1. The method of eliminating stray field heating in magnetic parts of an induction electric furnace, which consists in intercepting the stray magnetic flux by a non-magnetic metal in solid condition located between the point of emanation 10 and the magnetic parts and in converting the flux into heat within this non-magnetic metal.

2. The method of eliminating stray field heating in magnetic parts of an induction electric furnace, which consists in providing a solid electrical path for eddy-current generation between the furnace inductor and the magnetic parts and extending only part of the way around the furnace inductor, which path is opaque to passage 15 of flux through it, in transforming the flux into induced current and in conducting the heat away from the point of eddy-current heat generation.

3. In an induction electric furnace, a furnace inductor coil, magnetic frame parts for the furnace at a distant point from the coil and a shield of non-magnetic, highly conductive solid 25 material located between the coil and the frame parts in the line of travel of stray flux and of sufficient thickness to transform into heat substantially all of the stray flux passing into it.

4. In an induction electric furnace, an inductor coil, supporting structure for the inductor coil containing magnetic parts and a non-magnetic solid metallic shield between the inductor coil and the magnetic parts to cut off the magnetic flux from the parts, the shield being substantially discontinuous about the inductor.

5. In an electric induction furnace, an inductor coil, supporting structure for the inductor coil containing magnetic parts, and a non-magnetic 40 solid metallic shield between the inductor coil and the magnetic parts and closer to the inductor at points located between the inductor coil and parts than at the extremities of the shield.

6. In an electric induction furnace, an inductor coil, supporting structure for the inductor coil containing magnetic parts and a non-magnetic solid metallic shield having a thickness greater 45 than the effective depth of penetration of the magnetic flux placed between the inductor coil and the magnetic parts.

7. In an electric induction furnace, an inductor coil, supporting structure for the inductor coil containing magnetic parts and a non-magnetic solid metallic shield of substantially greater 55 lateral extent than the magnetic parts between the inductor coil and the magnetic parts.

8. In an electric induction furnace, an inductor coil, supporting structure for the inductor coil containing magnetic parts and a non-magnetic solid metallic shield of a thickness greater 60 than the effective depth of the penetration of the flux and of substantially greater lateral extent than the magnetic parts between the inductor coil and the magnetic parts.

9. In an electric induction furnace, an inductor coil, supporting structure for the inductor coil containing magnetic parts and a non-magnetic solid metallic shield of high electrical and heat 65 conductivities between the inductor coil and the magnetic parts.

10. In an electric induction furnace, an inductor coil, supporting structure for the inductor coil containing magnetic parts and a discontinuous non-magnetic solid metallic shield of high 75

electrical conductivity between the inductor coil and the magnetic parts.

11. In an electric induction furnace, an inductor coil, supporting structure for the inductor coil containing magnetic parts and a discontinuous non-magnetic solid metallic shield of high electrical and heat conductivities between the inductor coil and the magnetic parts.

12. In an electric induction furnace, an inductor coil, supporting structure for the inductor coil containing magnetic parts and a flat non-magnetic metallic plate between the inductor coil and the magnetic parts.

13. In an electric induction furnace, an inductor coil, supporting structure for the inductor coil containing magnetic parts and a flat copper plate between the inductor coil and the magnetic parts.

14. In an electric induction furnace, an inductor coil, supporting structure for the inductor coil containing magnetic parts and a non-magnetic metallic solid shield of high electrical and heat conductivities between the inductor coil and the magnetic parts and extending uninterruptedly to an angular extent measured about the furnace substantially as great as the angular extent of the magnetic parts to be protected.

15. An inductor furnace comprising a crucible,

an inducing winding surrounding said crucible, a metallic framework outside of said winding to be protected from the magnetic effects of the current in said winding and a copper shield located between said winding and framework and continuous and imperforate throughout the horizontal angular extent of said framework.

16. An inductor furnace comprising a crucible, an inducing winding surrounding the said crucible, a metallic framework outside the said winding and a solid copper shield interposed between said winding and said framework and shielding said framework throughout the entire horizontal angular extent of said framework.

17. A coreless induction metal melting furnace comprising a crucible, a primary winding surrounding said crucible for producing a magnetic field in an interior region of said crucible, a supporting framework made of ferrous metal for said winding and said crucible and a shield of sheet copper having angular extent about said winding as great as the angular extent of the supporting framework and interposed between said winding and said framework, said shield having a thickness at least as great as its depth of magnetic penetration.

EDWIN FITCH NORTHRUP.
